UNITED STATES PATENT OFFICE

2,009,333

METAL-CLAD ELECTRIC SWITCH GEAR

Archibald Allan, Tynemouth, England, assignor
to A. Reyrolle & Company Limited, Hebburn-
on-Tyne, England, a company of Great Britain

Application March 17, 1933, Serial No. 661,404
In Great Britain March 24, 1932

18 Claims. (Cl. 175—298)

This invention relates to metal-clad electric switchgear and has for its primary object to provide an improved arrangement of the metal-clad apparatus (such for example as circuit-breakers, reactors and transformers) forming part of or associated with a switchgear layout for an electric power station or substation, whereby considerable economy can be effected both in the size and the cost of the switchgear.

- 10 Metal-clad switchgear according to the present invention comprises a chamber containing a busbar or other conductor immersed in an insulating liquid, a movable conductor which in its operative position projects through an orifice in the wall of the chamber and makes contact with the busbar or other conductor therein, and a sealing device so arranged as to seal the orifice in a liquid-tight manner when the conductor is withdrawn from the chamber. The arrangement is especially suitable for the case of a movable conductor connecting two conductors each mounted in a chamber containing insulating liquid, the movable conductor in this case being withdrawable into or through one of the chambers whilst a sealing device is provided to seal the orifice in one or in each of the chambers. Thus one convenient arrangement according to the invention may comprise a tank containing a circuit-breaker or other electrical apparatus, a chamber containing a busbar or like conductor immersed in an insulating liquid, an insulated conductor so mounted that it can project into the apparatus tank and the busbar chamber to connect the busbar to a terminal of the apparatus and can be withdrawn from the busbar chamber towards or into the apparatus tank, and a sealing device so arranged as to seal the orifice in the wall of the busbar chamber in a liquid-tight manner when the insulated conductor is withdrawn therefrom into the tank. The orifices in the walls of the two chambers through which the insulated conductor passes are preferably connected together by a metal trunk carried at one end by one of the chambers and provided at the other end with a flexible extension detachably connected to the wall of the other chamber. The detachable connection may take various forms but in one convenient arrangement the flexible extension is mechanically forced, for example, by a toggle mechanism, into close contact with the chamber wall around the orifice so as to seal the joint in a liquid-tight manner.

An alternative arrangement according to the invention comprises a chamber containing a busbar or like conductor immersed in an insulating liquid, a tank containing a circuit-breaker or other electrical apparatus movably mounted with respect to the busbar chamber for isolating purposes, an insulated conductor mounted on the apparatus tank and connected to a terminal of the apparatus therein and so arranged that when the apparatus tank is in its operative position the insulated conductor projects through an orifice in the wall of the busbar chamber and makes contact with the conductor therein, and a sealing device so arranged as to seal the orifice in the busbar chamber in a liquid-tight manner when the apparatus tank is moved to withdraw the insulated conductor from such chamber.

Except in arrangements, such as that just mentioned, wherein the movable conductor is fixed in position on a movable tank, the movements of the conductor are preferably effected by fluid-pressure operated means, for example, by arranging the insulation around the conductor or a metal sheath surrounding such insulation to act as a piston in a fixed tubular sleeve.

The manner in which the sealing device is mounted may vary. In one simple arrangement the device is in the form of a plug detachably carried by the movable conductor so that it will remain in and seal the orifice in the chamber wall when the conductor is withdrawn. Alternatively the device may be in the form of a plug hinged or otherwise mounted on the wall of the chamber to be sealed, means being provided for moving the plug into its sealing position when the conductor is withdrawn. In a preferred arrangement the sealing device is in the form of a sluice valve which is carried on the wall of the chamber to be sealed and can slide to seal the orifice when the conductor is withdrawn.

It will be appreciated that the provision of the sealing device according to the invention ensures that there will always be a body of insulating liquid between the busbar or other conductor and the earthed metal wall of the chamber around the orifice even at the moment when the insulated conductor is being withdrawn from the chamber, and thereby renders it unnecessary to provide the large clearance distance between these points which would otherwise be required to prevent risk of a flashover if the space between these points were at any time filled with air. This makes it possible considerably to reduce the size of the chamber, and therefore also the cost of the whole installation, since it is only necessary to separate the busbar from the walls of the chamber by a distance sufficient to prevent risk of a flashover in oil. Another great advantage of

the invention is that it enables the removable portions of the switchgear to be separated from oil-filled chambers in the stationary part without the necessity of draining the oil out of such chambers and therefore without introducing the dangerous condition of air clearance to a live contact at any time even during actual removal of the circuit-breaker or other apparatus.

The invention may be carried into practice in a variety of ways, but some convenient practical arrangements according thereto, as applied to oil-immersed circuit-breakers forming part for example of a high voltage switchgear layout, are illustrated in the accompanying drawings, in which

Figure 1 is an elevation (with the circuit-breaker tank in section) of an arrangement in which the circuit-breaker controls a simple connection from a busbar to a feeder or other circuit,

Figure 22 illustrates an alternative driving arrangement for the withdrawable conductor,

Figure 23 illustrates a further alternative duplicate busbar arrangement, and

Figures 24 and 25 respectively illustrate modifications of the arrangement of Figure 23.

In the arrangement shown in Figures 1-6, which is applicable to a simple installation in which the circuit-breaker controls a connection from a busbar to a feeder or other circuit, the circuit-breaker oil tank 50 rests on the ground and two oil-filled chambers 60 and 70 are mounted above the tank on supporting pillars or a suitable framework (not shown). The chamber 60 constitutes the busbar chamber and contains a contact 61 to which the sections of the busbar 62 are directly connected.

The chamber 70 is associated with the feeder circuit and contains a contact 71 carried by a

supporting insulator 72. Extending down from this contact 71 to the bottom wall of the chamber 70 is a hollow insulator 73 which surrounds in an oil-tight manner an orifice in the chamber wall, and a sealing end 74 on the feeder-cable 75 is inserted through this orifice so as to make connection with a terminal within the top of the insulator 73 connected through the insulator to the main feeder contact 71. The cable sealing end 74 carries a flange 76 which can be secured to the chamber wall around the orifice with suitable insulation to isolate the cable sheath from the chamber wall. A small compartment is thus enclosed between the sealing end 74 and the hollow insulator 73 and this compartment may be filled with oil from the chamber 70 through a valve on the insulator 73. Means are provided to allow the oil to be drained off from this compartment after closing the valve, when it is desired to remove the sealing end, and it will be appreciated that this arrangement permits removal of the sealing end without the necessity for draining the oil out from the chamber 70 itself.

The circuit-breaker comprises two fixed main contacts 51, 52 and a movable bridging contact member 53, the arrangement preferably being such as to give six breaks in series. The bridging contact member 53 is operated by suitable mechanism, indicated at 54, carried by the cover plate 55 of the oil tank 50 containing the circuit-breaker.

Extending upwardly at a small angle to the vertical from each of the fixed main contacts 51, 52 of the circuit-breaker is a hollow condenser 30 insulator 80, comprising short overlapping conducting layers 81 interleaved with insulating layers and surrounded in its upper portion by a metal sleeve 82, which projects through an orifice in the cover plate 55 of the tank and is provided with a flange 83 bolted to the cover plate. The lower end of each hollow insulator 80 is closed in an oil-tight manner by a metal cap 84 connected to the main fixed circuit-breaker contact 51 or 52, and a metal tube 85 extends up from this cap 84 within the lower portion of the insulator. At the upper end of each insulator the surrounding metal sleeve 82 carries a flange 86, to which is bolted a metal casing 88 including a cylindrical metal trunk 91 surrounded by an annular chamber 92 in which current transformers can be located. Around the upper end of the metal trunk 91 is a flexible metal bellows 93, which is attached to the top of the casing 88 and can be clamped to the bottom of a valve chest 55 mounted below the appropriate oil-filled chamber 60 or 70, a metal shield 94 being provided around the bellows 93 to protect it from damage. The busbar contact 61 or the feeder contact 71, as the case may be, is in line with the axes of the metal trunk 91 and the hollow insulator 80, and communication between the chamber 60 or 70 and the tubular compartment formed by the trunk and the insulator can be cut off by means of a valve in the valve chest in a manner to be described later.

Mounted to slide longitudinally in this tubular compartment is an insulated conductor 100, which serves when in its operative position to connect the busbar contact 61 or the feeder contact 71 to the inner metal tube 85 in the insulator 80 and thence to the main circuit-breaker contact 51 or 52. This insulated conductor comprises a rigid central tube 101 surrounded by insulation 102, which in the case of the higher

voltage installations is in the form of condenser insulation as shown, the insulation being enclosed for part of its length by an outer metallic sheath 103, which engages with the metal trunk 91. The 5 central tube 101 serves to contain flexible connections 104 between contacts at the upper and lower ends of the insulated conductor. The lower contacts (see Figure 6) are in the form of outwardly spring-pressed plungers 105 engaging 10 with the metal tube 85 and carried in a metal block 106 to which the lower ends of the flexible leads 104 are connected. The upper contacts consist of a bundle of butt contacts 107 independently spring-pressed in a longitudinal direction 15 so as together to constitute a self-aligning butt contact for engagement with the busbar contact 61 or the feeder contact 71.

The insulated conductor can be withdrawn downwards from its operating position into an 20 isolating position, in which it lies within the tubular compartment formed by the metal trunk 91 and the insulator 80. In Figure 1 the conductor associated with the feeder is indicated in its raised operating position, whilst that associated 25 with the busbar is shown withdrawn into its isolating position, and Figure 2 similarly shows the conductor in the isolating position.

The movements of the withdrawable conductor are effected hydraulically by varying the oil pressure above and below the conductor, the metal sheath 103 on the conductor being provided with piston rings 108 so that the sheath acts as a piston movable in a cylinder constituted by the metal trunk 91. For this purpose an oil pump 110 driven by an electric motor 111 is mounted on the casing 90 and is connected by suitable ducts 112, 113 to the upper and lower ends of the tubular compartment in which the withdrawable conductor moves. The upper duct 112 opens into the transformer chamber 92 and is thus connected through the interior of the metal bellows 93 to the open upper end of the metal trunk 91. The lower duct 113 opens into the lower part of the casing 90 beneath the transformer chamber and is thus connected through openings in the flange 86 to the interior of the insulator 80, parts of the metal sheath 103 being cut away as indicated at 109 to permit the oil to flow into the lower end of the insulator 80. 50 Thus to raise the conductor the pump 110 is started up to withdraw oil from the upper end of the trunk 91 and to drive it into the interior of the insulator 80. To lower the conductor the pump is driven in the reverse direction, the 55 weight of the conductor assisting the movement. Alternatively a by-pass valve may be provided, which is opened to connect the two oil ducts together, the weight of the conductor being relied upon to effect the downward movement. If desired, instead of forming the sheath 103 as a piston moving in the cylinder formed by the metal trunk 91, the upper and lower parts of the tubular compartment may be separated from one another by a cup leather or sealing ring fixed in the 60 metal trunk and embracing the insulated conductor, so that the movements of the conductor are effected after the manner of a hydraulic ram.

Whilst the oil pressure may be utilized to hold the insulated conductor in its raised operating 70 position, it will usually be preferable to provide a mechanical latch for this purpose. A convenient construction of latch, which will hold the conductor either in its operating position or in its isolating position, is shown in Figures 2 and 5.

75 This latch consists of a ring 120 surrounding the

insulated conductor and pivoted about a vertical pin 121 at the lower end of the casing 90 at one side, the ring having two internal flanges 122 and 123 at different levels on opposite sides of the conductor. These flanges cooperate with grooves 124 and 125 in appropriate positions in the metal sheath 103 of the conductor, and to ensure correct positioning of the lower groove 125 a collar 95 is provided at the upper end of the metal trunk 91 with which the upper end of the metal sheath 103 engages when the conductor is in its raised position. The metal block 106 containing the lower contacts 105 similarly engages with a shoulder 86 at the lower end of the metal tube 85 within the insulator 80 for positioning the 15 upper groove 124 correctly when the conductor is in the isolating position. The latch ring 120 is moved to one side or the other about its pivot 121 by a pair of spring crank arms 139 on a horizontal shaft 131 suitably mounted outside the 20 metal sleeve 82. The shaft 131 is rotated by an operating arm 132 movable between fixed stops 133, 134 under the control of an operating rod 135 (see Figures 1 and 2). Thus with the conductor held in its raised position (as indicated 25 on the right-hand side of Fig. 1) by the engagement of the lower latch flange 123 in the lower groove 125, movement of the operating arm 132 to its other limiting position against the stop 134 will cause the spring arms 139 to release the 30 flange 123 from the groove 125 and will hold the upper latch flange 122 spring-pressed against the surface of the metal sheath 103, so that when the conductor reaches its isolating position (as indicated on the left-hand side of Figure 1) the 35 upper latch flange 122 will spring into engagement in the upper groove 124, the converse latch operation taking place when the conductor is raised. The latch operating mechanism is also utilized to operate through levers 136 a number 40 of auxiliary switches 137 housed in a box 138 on the casing 90 for indicating or interlocking purposes. The shaft of the auxiliary switches may also operate an indicator visible through a window 139 on the box 138 to indicate whether the 45 conductor is in its operating position or in its isolating position. The latch-operating rods 135 are actuated by suitable control mechanism which also operates contacts controlling the energization of the electric motors 111 for driving the 50 pumps, the energizing circuits for the pump motors being taken through certain of the auxiliary switches 137 controlled by the latch, the arrangement being such that a pump motor cannot be energized until the corresponding latch has been 55 released.

As has been mentioned, a valve is provided for sealing the orifice at the bottom of the busbar chamber 60 or the feeder chamber 70 when the insulated conductor has been withdrawn. A preferred construction for this valve is indicated in Figures 1 and 2 and is shown in detail in Figures 3 and 4. In this arrangement the valve is mounted in a valve chest 140 and is in the form of a sluice valve 141, which is caused to slide over the 60 orifice by rotation of a screwthreaded shaft 142 by means of a handwheel 143. The valve shaft 142 carries a notched disc 144, with which an arm 145 carried by a spindle 146 cooperates. This spindle 146 is connected to part of the control 70 mechanism for actuating the associated latch-operating rod 135, the arrangement being such that when the control mechanism is operated to cause the insulated conductor to be raised, the spindle 146 is rotated to cause the arm 145 to 75

engage in a notch on the disc 144 and thus to prevent the handwheel 143 from being rotated to close the valve. Since the arm 145 may not always be opposite a notch in the disc 144, the 5 spindle 146 is made of sufficient flexibility to permit it to twist when operated, so that after a slight rotation of the handwheel, the arm 145 will spring into the first notch on the disc and will thus lock the handwheel against further 10 rotation. In order to prevent energization of the pump motor 111 to raise the insulated conductor when the sluice valve is closed, the energizing circuit to the pump motor is controlled by an auxiliary switch operated by the sluice valve. For this 15 purpose the valve shaft 142 carries a worm 147 for operating a rotary auxiliary switch 148 housed in a casing 149 carried by the valve chest.

At one side of the valve chest 140, a by-pass valve is provided in the form of a rotary tapered 20 plug 150 having two holes 151, 152 bored in it. One of these holes 151 cooperates with two passages (one of which is indicated at 153) in the valve chest communicating respectively with the spaces above and below the valve itself. The second hole 152 controls a connection from the space 25 below the valve to the atmosphere. In the normal position of the plug 150 both holes are closed, but by rotating the plug into one position it is possible to complete a by-pass connection 30 through the hole 151 from one side of the valve to the other and at the same time a further connection from the space below the valve to the atmosphere. This allows the interior of the bellows 93 to be filled with oil from the upper chamber, when the bellows is again connected thereto after having been disconnected for removal of the circuit-breaker, without permitting entry of air into the upper chamber. The plug 150 can also be rotated into a further position in which 35 the by-pass connection is closed, but the connection of the space below the valve to the atmosphere through the hole 152 is open. This position is utilized to permit air to enter the interior of the bellows 93, when oil is being drained therefrom by a suitable draincock (not shown) prior to disconnection of the bellows from the upper chamber. In the body of the sluice valve 141 itself two small non-return valves 155, 156 are provided which act in opposite directions. The 40 valve 155 is arranged to open when the pressure in the upper chamber exceeds that within the bellows by a predetermined amount to permit oil to flow into the bellows when contraction of the oil below the valve takes place as the result of 45 temperature variations, and the valve 156 likewise allows oil to flow out from the bellows into the upper chamber in the event of excessive pressure being set up within the bellows owing to expansion of the oil therein due to temperature 50 changes.

The above arrangement may be modified in 55 various ways. Thus for instance the hollow insulator 89 in the circuit-breaker tank may be taken right past the circuit-breaker fixed contact and may be of such a length as to permit the whole of the withdrawable conductor to lie within the tank itself in the isolating position, thus enabling the overall height of the switchgear to be still further reduced. Again by leaving the lower 60 end of the hollow insulator in the tank open, the raising of the insulated conductor could be effected hydraulically by raising the pressure in the gas space in the tank itself, so that oil from the tank is forced up within the hollow insulator 65 to drive the conductor in front of it.

The foregoing arrangement has been described and illustrated as applied to a circuit-breaker controlling a simple connection from a busbar to a feeder circuit, but it is equally applicable to the case of a duplicate busbar layout wherein each 5 busbar is connected to the feeder or other circuit through a separate circuit-breaker, and generally to all cases where it is impossible for the fixed circuit-breaker contact with which the insulated conductor cooperates to be alive from another 10 circuit during movement of the insulated conductor from one position to the other. Thus in the arrangement actually illustrated in Figures 1-6 the metal sheath 193 of the conductor connects 15 the circuit-breaker contact through the tube 85 to the earthed metal trunk 91, and even if the metal sheath were shortened to avoid such a direct earth connection, the inclusion of metal layers in the insulation around the conductor would in many instances reduce the dielectric value of the 20 insulation between the circuit-breaker contact and the earthed metal trunk to too low a value. In cases therefore where the circuit-breaker contact may be alive from another circuit and where 25 it is desirable to employ condenser insulation around the conductor, it is preferable to modify the construction of the insulated conductor to avoid risk of flash-over from the main circuit-breaker contact to earth.

Figure 7 illustrates such a modified form of 30 insulated conductor in its application to a duplicate busbar installation, wherein a single circuit-breaker provided with busbar selecting means controls the connections from both busbars to the feeder or other circuit. In this arrangement three oil-filled chambers are mounted 35 above the circuit-breaker oil tank, two of these chambers respectively containing contacts connected to the two busbars, whilst the third contains a contact connected to the feeder or other 40 circuit. The three contacts in the upper chambers are connected to the circuit-breaker fixed contacts by withdrawable insulated conductors, the conductors associated with the two busbar 45 contacts both cooperating with one of the main circuit-breaker contacts, whilst the other main circuit-breaker contact cooperates with the conductor associated with the feeder contact.

Figure 7 shows the two busbar chambers 170 and 175 respectively containing contacts 171 and 50 176 connected to the two busbars 172 and 177, and the connections therefrom to one of the fixed main circuit breaker contacts 181 contained within the circuit-breaker tank 180. The other circuit-breaker contact and the connection therefrom to the contact in the feeder chamber are not shown in the drawings but are preferably identical with the corresponding parts of the arrangement of Figures 1-6, and a description 55 of the connections to the busbars will be sufficient to enable the whole arrangement to be 60 understood.

Mounted one on either side of the circuit-breaker contact 181 are two hollow insulators 199, each surrounded at its upper portion by a 65 metal sleeve 191 carrying a flange 192 bolted to the cover plate 193 of the tank. Each insulator extends down past the circuit-breaker contact 181 and a connection from this contact passes 70 through the wall of the insulator to an internal ring contact 193. The insulator is closed at its lower end by a metal cap 194, carrying a short internal tube 195, and to grade the stresses set up the insulation is in the form of condenser insulation with suitably arranged overlapping short 75

metal layers 196 interleaved with the insulating layers. The flange 192 at the upper end of the metal sleeve 191 carries a metal tube 197 extending from within the top of the insulator 190 5 upwardly and having at its upper end a flange 198, to which is bolted a casing 200 containing a cylindrical metal trunk 201 surrounded by a current transformer chamber 202, the metal trunk constituting a continuation of the metal tube 10 197. The casing 200 and the parts carried thereby (including the motor-driven pump and the latch device) are substantially identical with the corresponding parts of the arrangement of Figures 1-6. A valve chest 205 containing a sluice 15 valve is mounted beneath the busbar chamber as in the previous arrangement and is similarly connected to the top of the casing 200 by a flexible metal bellows 206.

Mounted to slide longitudinally in the tubular compartment constituted by the metal trunk 201, the metal tube 197 and the hollow insulator 190, is an insulated conductor, which serves when in its operative position to connect the busbar contact 171 or 176 to the ring contact 193 and thus 20 to the main circuit-breaker contact 181. This insulated conductor comprises a rigid central tube 210 containing flexible leads connecting upper butt contacts 211 and lower spring contacts 212 in a manner similar to that described with reference to Figures 1-6. The central tube 210 is surrounded by layers of paper insulation 213 interleaved with overlapping short metal layers 214 and the upper part of the condenser insulation 30 is enclosed within a metal sheath 215. Spring contacts 216 are provided on one of the intermediate metal layers approximately midway between the lower end of the conductor and the lower end of the sheath 215. The metal sheath 215 carries piston rings 217 sliding in the cylindrical metal trunk 201 and is provided with upper and lower grooves 218, 219 coacting with the latch device in the casing 200 in a manner similar to that described for the arrangement of Figs. 1-6.

Since the metal sheath 215 slides within the metal trunk 201 it always remains in contact with earthed metal. When the insulated conductor is in its operative position with its upper butt contacts 211 engaging with the busbar contact and its lower spring contacts 212 engaging 45 with the ring contact 193 connected to the circuit-breaker contact the contacts 216 on the intermediate metal layer are earthed through the metal tube 197 (as indicated on the right-hand side of the drawings), whilst when the insulated conductor is in its isolating position (as shown on the left-hand side) the intermediate contact 216 engages with the ring contact 193 and the central conductors are earthed through the short tube 195 on the bottom cap 194 on the hollow 50 insulator 190. Thus in the isolating position the intermediate contact 216 may be alive, owing to the connection of the circuit-breaker contact 181 to the other busbar, but is located between two earthed points from which it is separated by 55 condenser insulation.

Thus with the circuit-breaker in operation connecting the feeder to, say, the busbar 177, the insulated conductors associated with the feeder and with this busbar will both be in their raised operative positions, whilst the insulated conductor associated with the busbar 172 is in its isolating position. If now it is desired to change over to the busbar 172, the main circuit-breaker contacts are opened, and the insulated conductor for the busbar 177 is lowered by operation of its pump and

latch device, the insulated conductor for the busbar 172 then being raised into its operative position and the main circuit-breaker contacts closed. The change-over can alternatively be effected without opening the main circuit-breaker contacts by first raising the insulated conductor for the busbar 172, so that the two busbars are connected together and to the feeder, and then lowering the conductor for the busbar 171. To remove the circuit-breaker for inspection or overhaul, the procedure is similar to that for the arrangement of Figures 1-6, namely, to open the circuit-breaker contacts and lower all the insulated conductors, after which the sluice valves are closed and the flexible bellows detached (after draining the surplus oil out of them). The circuit-breaker operating mechanism, if it is not arranged to be movable with the circuit-breaker, is then uncoupled, so that the circuit-breaker with the insulated conductors inside it can be removed laterally without the necessity of lowering it.

Instead of employing two separate tubes 197 and 201 in line with one another, the cylindrical metal trunk 201 may itself be extended downwardly to beyond the cover plate 182 of the tank, 25 the metal sleeve 191 and the hollow insulator 190 then extending right up to the flange 198 with the metal trunk 201 within the insulator. This modification is shown in Figure 8, which also shows a modified arrangement of the insulated conductor. In other respects the arrangement of Figure 8 is similar to that of Figure 7 and the same reference letters are employed. The insulated conductor employed in the arrangement of Figure 8 has a central tube 210 with the internal leads 30 connecting the upper and lower contacts 211, 212 and also a metal sheath 215 with its piston rings 217 and grooves 218, 219, as in the arrangement of Figure 7, but it differs from that arrangement in the form of the condenser insulation. In the arrangement of Figure 7 the overlapping short metal layers 214 in the lower part of the insulation extend from close to the central tube 210 at the lower end of the conductor at steadily increasing radii right up to the lower end of the 45 metal sheath 215, the spring contacts 216 being connected to a layer at an intermediate radius. In the arrangement of Figure 8, however, overlapping short metal layers 220 extend from close to the central tube 210 at the lower end of the conductor to a layer 221 at the full radius of the metal sheath 215 but at a position in the length of the conductor corresponding to that of the spring contacts 216 in the arrangement of Figure 7. This layer 221 is connected through the insulation to spring contacts 222. A further series of overlapping short metal layers 223 extends from close to the central tube 210 directly within the layer 221 up to the lower end of the metal sheath 215. At the upper end of the conductor, both in 50 this arrangement and in the arrangement of Figure 7, a similar series of overlapping short layers is provided between the sheath 215 and the upper end of the conductor, and the layers at the upper end are separated from the layers at correspond- 55 ing radii in the lower part of the conductor by a considerable axial distance which is such as to ensure adequate insulation between the circuit-breaker contact and the earthed metal trunk at all stages in the movement of the insulated conductor.

In the arrangements shown in Figures 1-8 the insulation around the withdrawable conductor has in each case been described as of the graded condenser type. Whilst this is generally prefer- 70 75

able in the case of apparatus used in high voltage installations on account of the reduction in dimensions which it allows, it may in some instances be more advantageous to employ an oil-filled type of insulating bushing around the conductor. Such an arrangement is shown in Figure 9 for a duplicate busbar installation. With the exception of the insulated conductor itself, this arrangement is identical with that shown in Figure 7 and the same reference letters are employed.

The withdrawable insulated conductor shown in Figure 9 comprises a rigid central tube 233, which may itself constitute the conductor or may enclose flexible leads in the manner above described, an upper butt contact 234 and lower spring contacts 232 being provided. A number of concentric insulating tubes 233 of graded lengths surround the central tube 233 within an outer insulating sleeve 234, the intervening spaces being filled with oil, so that the conductor is surrounded by a series of more or less uniformly thick layers of oil alternating with solid insulating layers. The outer sleeve 234 carries a metal sheath 235 provided with piston rings 236 and upper and lower latch grooves 237, 238 as in the previous arrangements. On lower voltage installations it is unnecessary to employ either condenser insulation or an oil-filled bushing arrangement, and simple insulation may be satisfactorily employed.

Figure 10 illustrates an alternative duplicate busbar arrangement, in which the necessity for employing a special arrangement of the condenser insulation around the withdrawable conductor is avoided. In this arrangement a single withdrawable conductor is utilized for controlling the connections from one circuit-breaker contact to the two busbar contacts, whilst the other circuit-breaker contact is connected to the feeder contact by a withdrawable conductor, which is arranged (together with the parts within which it moves) exactly in the manner shown in Figures 1-6. Figure 10 illustrates only the parts of the arrangement associated with the busbar side of the circuit-breaker.

In the arrangement of Figure 10, the two busbar chambers 250, 251 are mounted close together above the circuit-breaker tank, and each is provided beneath an orifice in its bottom wall with a valve chest 255 containing a sluice valve arranged in the manner previously described. The fixed circuit-breaker contact associated with the two busbars is supported beneath a hollow insulator 260 of oval cross-section carried by the cover plate 265 of the circuit-breaker oil tank, and is connected through the bottom of the insulator to a curved contact member 261. Extending up from the cover plate 265 towards the two busbar chambers is a metal casing 270 of generally oval cross-section, to the upper end of which is attached a flexible metal bellows 271 which can be clamped to a suitable oval fitting 256 carried beneath the two valve chests 255. This casing carries a hollow horizontal shaft 272 about which is pivoted an inner metal casing 280 carrying at its upper end a cylindrical metal tube 281 and at its lower end a metal sheath 282 for a condenser insulator 283. This insulator is closed at its lower end by a metal cap 284 having a projection 285 engaging with the curved contact member 261 and a metal tube 286 extends up from the cap 284 for a suitable distance within the insulator 283. The curvature of the contact member 261 is such that the projection 285 remains in engagement therewith when the casing 280 rocks about its pivot, and the metal tube 286 is thus

permanently connected to the fixed circuit-breaker contact. The metal tubes 281 and 286 are in line with one another and the metal casing 280 can be swung about the shaft 272 by suitable means (not shown) between two positions in which the axis of the tubular structure 281, 286 is in line respectively with the busbar contacts in the two busbar chambers 250 and 255. An insulated conductor 290 generally similar in construction to those employed in the arrangement of Figures 1-6, has its metal sheath 291 provided with piston rings 292 sliding within the metal tube 281, so that its lower spring contacts 293 always engage with the metal tube 286 whilst its upper butt contacts 294 can engage with either busbar contact. The metal sheath 291 has upper and lower grooves 295, 296 cooperating with a latch device 297 operated by a latch-operating rod 298 outside the casing 270 through a universal coupling 299. The conductor is raised and lowered hydraulically within the surrounding tubular structure by means of a motor-driven pump 273 carried by the casing 270, one side of the pump communicating directly with the interior of the casing 270 through a duct 274, whilst the other side communicates with the interior of the pivoted inner casing 280 through a pipe 275 coupled to the hollow shaft 272. Thus to change over from one busbar to another the circuit-breaker contacts are first opened and the insulated conductor is withdrawn into the tubular structure 281, 286, after which the inner casing 280 is rocked about its pivot to the other position and the conductor is raised again into engagement with the other busbar, the circuit-breaker contacts then being reclosed. The circuit-breaker can be removed for inspection or repair, when the insulated conductor has been withdrawn by detaching the flexible bellows 271 from the busbar chambers.

Figures 11 and 12 illustrate the application of the invention to a relatively low voltage three-phase switch-gear installation. In this arrangement three single-phase circuit-breakers 300 are mounted one behind the other on a wheeled truck 301. Each circuit breaker has two fixed main contacts 302 cooperating with a movable main contact 303 and four sets of arcing contacts 304 are provided with one set on each side of each fixed main contact. Extending vertically upwards from each circuit-breaker fixed main contact 302 is a tubular structure containing a withdrawable conductor, the six tubular structures being in line with one another. Each tubular structure comprises a hollow insulator 310 surrounded in its upper part by a metal sheath 311 and closed at its lower end by a metal cap 312 which is connected to the fixed circuit-breaker contact 302 and carries a metal tube 313 extending up within the insulator 310. The metal sheath 311 is flanged for attachment to an upward projection 306 on the cover plate 305 of the circuit-breaker tank and carries an upper casing 316 within which is mounted a cylindrical metal trunk 315. Attached to the top of the casing 314 is a flexible metal bellows 316, which can be clamped to the under side of a valve chest 320 containing a sluice valve arranged in the manner above described. The six valve chests 320 are respectively secured beneath six upper oil-filled chambers carried on a suitable supporting framework 321, three of these upper chambers constituting busbar chambers 322, whilst the other three are feeder chambers 323. Each of the busbar chambers 322 has in it a contact 324, having a downwardly extending cylindrical flange 75

325 connected to the busbar sections 326 and a similar contact is provided in each feeder chamber.

Mounted to slide within each metal trunk 315 is an insulated conductor surrounded by a metal sheath 329 provided with piston rings 331 and upper and lower latch grooves 332, 333 cooperating with a latch device 334 operated by an arm 335 outside the casing 314, the movements of the conductor being effected hydraulically by a pump 336 driven by an electric motor 337. The conductor is provided with upper and lower contacts 338, 339 cooperating respectively with the flange 325 on the busbar or feeder contact and with the metal tube 313. In order to carry the heavy current without introducing excessive end thrust on the movable conductor, these contacts 338, 339 are each in the form of a group of four brushes sliding edgeways in the cylindrical contact members with which they cooperate.

The contact in each feeder chamber 323 is connected through a metal trunk 340 into an intermediate chamber 341 containing a current transformer 342 and a cable earthing switch 343. From the intermediate chambers 341 leads pass down through lower chambers 344 to the feeder cables, and in each lower chamber 344 (as shown on the left-hand side of Figure 11) a tapping 345 is taken off for connection to a single-phase potential transformer. Each potential transformer is contained in a wheeled oil tank 350 from which projects upwardly a tubular structure 351 terminating in a flexible metal bellows 352 which can be clamped to a valve chest 353 mounted beneath the chamber 344 and containing a sluice valve, the tubular structure 351 serving to accommodate a withdrawable insulated conductor 354 cooperating at its lower end with a contact connected to the potential transformer winding and at its upper end with a contact 355 to which the tapping 345 leads. The whole potential transformer arrangement is analogous to the circuit-breaker arrangement, so that when the insulated conductor 354 has been lowered and the sluice valve closed, the bellows 352 can be detached from the valve chest 353 to permit the potential transformer tank 350 to be wheeled away for inspection or overhaul.

Figures 13-16 illustrate another application of the invention to three-phase switchgear for use on the lower voltages. In this arrangement the three phases of the circuit-breaker are all contained in a single oil-tank 380 mounted on wheels on the ground beneath a framework 361 carrying an upper chamber 362 for the external circuit connections. Six tubular structures 363 arranged in two rows extend upwardly from the circuit-breaker tank, each structure serving to contain a withdrawable insulated conductor arranged generally in the manner above described and terminating at its upper end in a flexible metal bellows 364. In this arrangement the three tubular structures on each side of the circuit breaker are so close together as to make it inconvenient to employ a separate sluice valve at the top of each structure, and the three sluice valves are accordingly arranged in a single valve chest 365 for operation by a single hand-wheel 366. Figure 15 indicates somewhat diagrammatically one arrangement of the valve chest 365, wherein the three sluice valves 367 are mounted integrally with one another and are driven by a screwthreaded shaft 368 carrying the handwheel 366 to cooperate with a wedging action with the orifices 369 in the upper wall of the

valve chest communicating with the upper chamber 362. It is sometimes desirable, however, to allow some slight relative movement between the three sluice valves in order to ensure correct seating over the orifices in the upper wall, and Figure 16 shows a modified construction for effecting this. In this modification the screw-threaded shaft 368 connected to the handwheel 366 cooperates with a nut 370 engaging with the first sluice valve 371, which is connected to the second sluice valve 372 through a compression spring 374 and a pull rod 375, the valve 372 being in turn connected to the third sluice valve 373 by another compression spring 376 and pull rod 377. Thus on closing the valves, the third valve 373 seats itself first and tight engagement is ensured by the spring 376 as the second valve 372 seats itself, the spring 374 forcing the second valve into engagement whilst the first valve 371 is positively driven against its seating.

In the arrangement illustrated in Figures 13-16 the circuit-breaker is utilized for controlling the connection from a feeder circuit 380 to a three-phase power transformer contained within an oil tank 381 mounted on wheels on the ground at one side of the circuit-breaker. The connections from the contacts in the upper chamber 362 to the power transformer windings are controlled by three insulated conductors 382 mounted in tubular structures 383 connected by flexible bellows 384 to a single valve chest 385 containing sluice valves arranged in the manner described with reference to Figure 15 or 16, the general arrangement of the insulated conductors 382 being similar to that above described for conductors 354 cooperating with circuit-breakers with the exception that the conductors are arranged horizontally and are withdrawable into the tubular structures 383 and the transformer tank 381 to permit removal of the tank for inspection or overhaul after detaching the flexible bellows 384 from the valve chest 385.

In the foregoing arrangements the device for sealing the orifice in the busbar or other chamber after withdrawal of the insulated conductor has in each case been in the form of a sliding sluice valve. The sealing device may however be arranged in other ways, and Figures 17 and 18 show two alternative arrangements in each of which the sealing device is in the form of a plug which can be swung away from the orifice within the busbar chamber itself by suitable mechanism, whilst Figures 19 and 20 show a further alternative arrangement in which the sealing device is in the form of a plug which is detachably carried by the withdrawable conductor and remains in and seals the orifice when the conductor is withdrawn.

Figure 17 also serves to show a convenient form of readily releasable joint between the flexible bellows and the busbar or other chamber (or the sluice valve chest) in place of bolts or like clamping devices. In this arrangement a flange 391 on the flexible bellows 390 is mechanically forced into close contact with a sealing ring 401 on the wall of the busbar chamber 400 around the orifice 402 therein so as to seal the joint in an oil-tight manner. This is effected by means of an arm 392 which is pivoted to a lug 393 on the chamber wall and is pressed against the flange 391 by a toggle mechanism constituted by the levers 394, 395. Thus, when the toggle is broken by rotating the spindle 396 carrying the lever 395, the flange 391 will be moved clear

of the chamber wall by the elasticity of the bellows 330 or by means of a separate spring.

- The sealing device shown in Figure 17 comprises a plug 410 carried on a ball joint 411 by an arm 412 extending from a loose sleeve 413 on a vertical shaft 414 in the busbar chamber 400. The sleeve 413 is pressed upwardly on the shaft 414 by means of a spring 415 and is provided with a curved slot 416 within which engages a pin 417 on the shaft. Thus when the shaft 414 is rotated by the arm 418 in the direction of the arrow, the pin 417 travels along the slot 416 so that the spring 415 forces the sleeve 413 up and lifts the plug 410 off its seating in the orifice 402. Further rotation of the shaft brings the pin 417 to the end of the slot 416, after which the plug 410 is bodily swung round with the shaft out of the path of the withdrawable conductor. The plug 410 with its operating mechanism can be removed through the top of the busbar chamber 400 for inspection or repair purposes, and a metal barrier 433 is provided to prevent risk of the plug swinging into the neighborhood of the busbar 404 itself during removal.
- In the alternative arrangement of Figure 18, the sealing plug 420 is carried by a crossbar 421 supported on two pairs of levers 422, 423, to which movement is imparted through gearing 424 by an arm 425 connected through a link 426 to a crank on an operating shaft 427, so that the plug 420 can be lifted from the orifice 402 and swung over into the position indicated in dotted line. The operating mechanism is supported on a framework 428 and can be lifted bodily out through the top of the busbar chamber 400, a barrier 433 being provided as in the arrangement of Figure 17.

In the arrangement shown in Figures 19 and 20, the sealing device is in the form of a metal plug carried by the withdrawable conductor itself, so that the orifice in the busbar or other chamber is sealed when the conductor is moved into its isolating position. The plug 430 is provided on its under surface with packing material 431 and also carries a cup leather or U-shaped leather 432 around its edges, so that when the conductor is in its isolating position the plug rests on an inwardly directed flange 441 in the orifice in the wall of the busbar chamber 440 and fits within a cylindrical part 442 of the chamber wall, the pressure on the upper side of the plug thus ensuring an oil-tight joint. On its upper side the plug 430 is recessed at 433 to form a contact for engaging with spring-finger contacts 443 connected to the busbar when the conductor is moved into its operating position.

The plug 430 is detachably mounted on the withdrawable conductor, and various forms of detachable connection may be employed, such as a yielding or spring grip joint or a removable clip or cotter pin. In one convenient arrangement the plug 430 carries a ball 434 projecting from its under surface, which is held by spring rings 435 within a split cylindrical sleeve 436 so arranged as to permit slight movement for self-alignment purposes. This sleeve 436 is gripped between two clamping members, one of which 437 is formed integral with a cap on the upper end of the withdrawable conductor, whilst the other 438 is detachable. Thus when the conductor has been withdrawn until the plug 430 seals the orifice in the busbar chamber 440, the clamping member 438 can be detached and the circuit-breaker can be moved laterally without further lowering of the insulated conductor as

would be necessary with a spring joint or cotter pin fastening. It should be mentioned that the flexible bellows 445 is in this arrangement preferably arranged to remain on the busbar chamber 440 when the circuit-breaker is removed, the bellows being detached both at its upper and at its lower ends and lifted up around the neck 442 of the busbar chamber to permit ready access to the clamping members 437, 438 and free movement of the circuit-breaker.

Although more especially intended for switchgear of the vertical type, wherein the busbar or other chambers are located above the circuit-breaker tank and the insulated conductors are movable vertically or at a small angle to the vertical, the invention is also applicable to switchgear wherein horizontal isolating movements are employed. One such arrangement has already been described with reference to Figures 13-16 as far as the application of the invention to power transformers is concerned, and it will be readily appreciated that similar arrangements with horizontal isolating movements can also be applied to circuit-breakers and to reactors and other apparatus forming part of a switchgear layout, and that arrangements with vertical or approximately vertical isolating movements such as have been described for circuit-breakers are equally applicable to power transformers and reactors and other apparatus. Thus in a circuit-breaker arrangement the insulated conductors may be movable more or less horizontally through the side walls of the circuit-breaker tank to cooperate with busbar or other chambers located at the sides of the tank, with sluice valves or other sealing devices for sealing the orifices in the walls of the side chambers and also of the circuit-breaker tank. Again the busbar or other chambers may, if desired, be mounted beneath the circuit-breaker tank, in which case the associated insulated conductors would be movable through orifices in the bottom of the tank and in the top of the fixed chambers, appropriate sealing devices being provided. This arrangement may be modified by mounting, say, the feeder chamber beneath the circuit-breaker tank and the busbar chamber or chambers above the tank, or again in a duplicate busbar installation one busbar chamber may be above the circuit-breaker and the other beneath it so that a single insulated conductor can be moved to project from the circuit-breaker tank alternatively into either busbar chamber for busbar selection purposes, the feeder chamber being mounted either above or below the circuit-breaker.

Whilst it is generally preferable for a variety of reasons to withdraw the insulated conductor towards or into the tank containing the circuit-breaker or other apparatus for isolating purposes in the manner above described, it may in some instances be more convenient to adopt other arrangements. Thus the conductor may be withdrawable from the circuit-breaker tank into the fixed part of the switchgear (an example of such an arrangement being shown in Figure 23 to be described later), whilst in other cases the insulated conductors may be fixed in position on the circuit-breaker tank, isolation being effected by bodily moving the whole tank. An example of the latter arrangement is illustrated in Figure 21 for the case of switch gear of the horizontal draw-out type.

In the arrangement shown in Figure 21 a hood 451 is mounted over the circuit-breaker tank 450 and the whole circuit-breaker is movable hori-

zontally on wheels on a supporting framework 452. The circuit-breaker contacts are connected through the hood 451 to two (or more) laterally projecting plug members 453, which move with the circuit-breaker and cooperate respectively with a busbar chamber 460 and a feeder chamber 461. A flexible metal bellows 454 is attached to the hood 451 around each plug member 453 and can be clamped to a valve chest 462 containing a sluice valve 463 mounted on the appropriate fixed chamber. The bellows 454 are given sufficient elasticity to permit movement of the circuit-breaker sufficient for isolating purposes without detaching them from the valve chests, and the drawings show the circuit-breaker in its isolating position with the sluice valves closed ready for the bellows to be detached (if desired) to allow the circuit-breaker to be removed completely for overhaul. A generally analogous arrangement may also be employed in switchgear of the vertical draw-out type, where the lifting and lowering of the whole circuit-breaker does not present great practical difficulties.

In the arrangements of Figures 1-20 the movements of the insulated conductors have been described as effected hydraulically, but it will be appreciated that other means may be employed for this purpose, and Figure 22 illustrates by way of example a modified arrangement in which mechanical operation is employed. This arrangement is shown as applied to a circuit-breaker for use on the lower ranges of voltage. In this arrangement the circuit-breaker is contained in an oil tank 480 and has fixed main contacts 481 cooperating with a movable bridging main contact member 492, auxiliary arcing contacts 483 being associated with each fixed main contact. Extending upwardly from each fixed main contact 481 is a hollow cylindrical insulator 484 surrounding a metal tube 485 connected to the fixed main contact and surrounded by a metal sleeve 490 supported on the cover plate 486 of the circuit-breaker tank. The metal sleeve 490 is extended upwardly to form a casing 491 containing a pinion 492 on an operating shaft 493, and a flexible metal bellows 494 is attached to the top of the casing 491 so that it can be clamped beneath a valve chest 495 mounted beneath the busbar or other chamber 496. Suitably guided within the tubular compartment inside the metal sleeve 490 is an insulated conductor 500 having an upper butt contact 501 cooperating with the contact in the upper chamber 496 and lower spring finger contacts 502 engaging with the metal tube 485. The insulated conductor is surrounded by a metal sheath 503 on which is formed a toothed rack 504 engaging with the pinion 492. Thus rotation of the pinion shaft 493 will cause the insulated conductor 500 to move up into its operating position in which it connects the circuit-breaker contact 481 to the contact in the upper chamber 496, or to be withdrawn into the isolating position shown.

The arrangements above described wherein a sealing device is provided for the busbar or other chambers, have the great advantage that they enable the overall height of the whole switchgear, especially for very high voltages, to be considerably reduced with corresponding great economy in the cost of the supporting structure, since the busbar or other chambers need be made large enough only to provide the clearances necessary for oil insulation. Moreover there is no need for the building in which the switchgear is housed in the case of an indoor insulation, to be of much

greater height than the switchgear itself since overhead lifting and lowering gear can be entirely eliminated. This fact makes it practicable, if desired, to mount the two busbar chambers (in the case of the duplicate busbar installation) one on top of the other without great increase in the height of the structure, thus enabling a single tubular structure to be employed containing an insulated conductor or conductors which may thus serve for busbar selection as well as for isolation purposes. Whilst it is possible, in cases where the overall height of the structure is not of primary importance, to design a single insulated conductor which can be employed in this manner for busbar selection and for isolation purposes, it is preferable to employ two concentric insulated conductors within the single tubular structure.

Such an arrangement is illustrated in Figure 23. In this arrangement the two busbar chambers 510, 520 are disposed one above the other above the circuit-breaker tank, part of the cover plate of which is shown at 530, and respectively contain annular busbar contacts 511, 521 connected to the busbar sections 512, 522. The upper busbar chamber 510, has an upward extension in the form of a cylindrical metal trunk 513, and the two chambers are connected together by another cylindrical metal trunk 514. A third cylindrical metal trunk 523 surrounded by a current transformer chamber 524 extends downwardly from the lower busbar chamber 520 in line with the trunks 513, 514 and carries at its lower end a valve chest 525 containing a sluice valve 526. The tubular structure constituted by the three metal trunks is continued in the circuit-breaker tank by a hollow insulator 531 surrounded by a metal sleeve 532 attached to the cover plate 530, the lower end of the insulator 531 being closed by a metal cap 533 connected to the fixed circuit-breaker contact. This metal cap carries a vertical contact rod or tube 534 projecting centrally upwards within the insulator 531 and also a shorter metal tube 535 concentrically surrounding the rod 534 and formed into contacts 536 at its upper end. A flexible metal bellows 537 is attached to the cover plate 530 of the circuit-breaker tank and can be clamped beneath the valve chest 525.

Insulation 541 around a tubular conductor 540 carries midway in its length a short metal sleeve 542 provided with piston rings 543 sliding within the metal trunk 523 and with a latch groove 544, and a further sleeve 545 with a second latch groove 546 is provided towards the upper end of the insulation. The lower end of the tubular conductor 540 extends beyond the insulation 541 and constitutes a contact which can engage with the contacts 536 connected to the circuit-breaker contact, and spring contacts 547 are provided at the upper end of the conductor.

A second tubular conductor 550 is surrounded by insulation 551 carrying towards its lower end a sleeve 552 provided with piston rings 553 sliding within the first tubular conductor 540, and two further sleeves 554, 556 respectively provided with latch grooves 555, 557 are provided towards the upper end of the insulation. The insulation 551 extends beyond the lower end of the conductor 550 which constitutes a contact for engagement with the contact rod 534 connected to the circuit-breaker contact, and spring contacts 558 are provided at the upper end of the conductor 550.

The latch grooves 555, 557 on the inner con- 75

ductor 550 cooperate with a latch device 515 mounted at the top of the metal trunk 514 and operated by mechanism (not shown) similar to the latch-operating mechanisms employed in the arrangements above described. A similar latch device 527 is provided at the top of the metal trunk 523 for cooperation with the latch grooves 544, 546 on the outer conductor 540. The movements of the two insulated conductors 540, 550 are effected hydraulically by means of a pump (not shown) connected by ducts 528, 529 respectively to the busbar chambers 520, 510 through the current transformer chamber 524 and to the interior of the flexible bellows 537 and the hollow insulator 531 through the valve chest 525. In this arrangement the two insulated conductors 540, 550 are withdrawable upwards away from the circuit-breaker tank into their isolating positions, and the drawings show the outer conductor 540 held in its lower or operative position by the engagement of the latch device 527 in the latch groove 546 and the inner conductor 550 held in its upper or isolating position by the engagement of the latch device 515 in the latch groove 555. To change over the connections, the circuit-breaker contacts are opened and the latch device 527 is operated to release the outer conductor 540, the pump then being started up in a direction to raise the conductor, the inner conductor 550 being held by its latch. The outer conductor 540 then moves upwards into its isolating position, wherein the conductor is earthed by engagement of its upper contacts 547 with the metal trunk 514, the conductor being held in this position by engagement of the latch device 527 in the lower latch groove 544. The latch device 515 is now operated to release the inner conductor 550 and the pump is started up in the reverse direction. This drives the inner conductor down until the latch device 515 engages in the latch groove 557 to hold the conductor in its operative position in which it constitutes a connection from the upper busbar contact 511 to the rod contact 534 and thence to the circuit-breaker contact. Reclosing of the circuit-breaker contacts will now complete the change-over. It should be mentioned that the arrangement of the two insulated conductors is such as to permit the change-over to be effected on load without opening the circuit-breaker contacts, if desired, the inner conductor 550 first being lowered so that both conductors are in their operative positions and the two busbars are connected together, after which the outer conductor 540 is raised into its isolating position. When both conductors have been raised into their isolating positions, the sluice valve 526 can be closed, and after detaching the flexible bellows 537 from the valve chest 525, the circuit-breaker can then be removed for inspection or overhaul.

Figures 24 and 25 illustrate two modifications of the arrangement of Figure 23, wherein a single movable insulated conductor is employed in combination with one or more sliding insulators carrying contacts to effect busbar selection, the insulated conductor being withdrawable downwards towards the circuit-breaker tank for isolating purposes.

In the arrangement of Figure 24 the two busbar chambers 560, 570 are disposed one above the other above the circuit-breaker tank 580 and respectively contain annular busbar contacts 561, 571 connected to the busbar sections 562, 572. The two busbar chambers are connected together by a cylindrical metal trunk 563 and a valve chest 573 containing a sluice valve 574 is mounted

beneath the lower busbar chamber 570. Extending upwardly from the fixed circuit-breaker contact associated with the busbars is a hollow insulator 581 closed at its lower end by a metal cap 582, which is connected to the circuit-breaker contact and carries a metal tube 583 fitting within the insulator. The insulator 581 is surrounded by a metal sleeve 584 which is carried by the cover plate 585 of the tank 580 and is connected at its upper end to a casing 586 containing a metal trunk 587 surrounded by a current transformer chamber, the upper end of the casing 586 being connected to the valve chest 573 by a flexible bellows 588 as in the arrangement of Figures 1-6. An insulated conductor 590 having upper and lower spring contacts 591, 592 is surrounded by a metal sheath 593 provided with piston rings 594 sliding within the metal trunk 587 and also with latch grooves 595, 596 cooperating with a latch device 597 at the bottom of the trunk, the movements of the conductor being effected by means of a pump (not shown) communicating with the casing 586 through ducts 589.

A hollow insulator 600 carries a collar 601 with piston rings 602 sliding within the metal trunk 563 between the two busbar chambers, and has metal rings 603, 604 at its ends provided with spring contacts cooperating with the busbar contacts 561, 571, the upper metal ring 603 being connected to a metal tube 605 extending down within the insulator for most of the length thereof. This insulator 600 can be raised or lowered by means of a second pump (not shown) connected by ducts 564, to the upper and lower ends of the metal trunk 563. The collar 601 carries latch grooves 606, 607 cooperating with simple latch devices 565, 566 to hold the insulator 600 in its two operating positions. An insulating tube 567 fixed in the top of the upper busbar chamber 560 has a collar 568 at its lower end provided with piston rings which engage within the metal tube 605 within the insulator and serve to cut off communication between the interior of the insulator and the upper busbar chamber.

In the drawings the parts are shown in position to connect the fixed circuit-breaker contact to the upper busbar 562, the connection including the upper metal ring 603, the metal tube 605, the insulated conductor 590 and the metal tube 583. When it is desired to change over the connections the circuit-breaker contacts are opened, and the second pump is started up in a direction to draw oil from the upper busbar chamber 560 and drive it into the lower busbar chamber 570 thus raising the insulator 600, the latch device 566 having first been released. The insulator 600 is held by the latch device 565 in its raised position, in which the lower metal ring 604 constitutes a direct connection between the lower busbar contact 571 and the upper spring contacts 591 on the insulated conductor 590. The change over is completed by reclosing the circuit-breaker contacts. For isolating purposes the insulated conductor 590 is lowered into its isolating position within the tank 580 and the tubular structure above the tank, and by closing the sluice valve 574 and detaching the bellows 588 from the valve chest, the circuit-breaker can be removed for inspection purposes.

The arrangement of Figure 25 differs from that of Figure 24 in that it permits the change-over from one busbar to the other to be effected on load, if desired, without opening the circuit-breaker contacts. Parts of the arrangement are identical with the corresponding parts of Fig-

ure 24 and the same reference numerals are employed for such parts. In this arrangement a fixed insulating cylinder 610 extends up from the bottom of the lower busbar chamber 570 to the top of a metal trunk 620 provided above the upper busbar chamber 560. Within this insulator 610 is a metal tube 611 whose upper and lower ends are connected through the insulator 610 to metal rings 612, 613 respectively adjacent to the busbar contacts 561, 571. The upper contacts on the movable insulated conductor 590, which in this instance may be in the form of butt contacts 599, engage with a contact 614 formed on the lower end of the metal tube 611. Thus when the movable conductor 590 is in its raised operative position, the fixed circuit-breaker contact is connected to the two metal rings 612, 613 around the insulating cylinder 610. The connection from the ring 612 to the busbar contact 561 is controlled by a contact 631 on the lower end of a movable hollow insulator 630 having at its upper end an annular end cap 632 provided with external piston rings 633 sliding in the metal trunk 620 and with internal piston rings 634 sliding on a metal sheath 615 around the top of the insulating cylinder 610. The end cap 632 also has latch grooves 635, 636 cooperating with latch devices 621, 622 respectively at the top and bottom of the metal trunk 620. Thus when the insulator 630 is held by the latch 621 in its upper position, its contact 631 bridges the gap between the ring 612 and the busbar contact 561, whilst when the insulator is held in its lower position by the latch 622, the ring 612 is insulated from the busbar contact 561. The movements of the insulator 630 are controlled by a pump connected through ducts 623, to the upper and lower ends of the trunk 620.

The connection between the lower metal ring 613 and the lower busbar contact 571 is similarly controlled by a contact 641 on a movable insulator 640 having an end cap 642 with external and internal piston rings 643, 644 engaging with the metal trunk 563 and an intermediate metal sheath 616 around the insulating cylinder 610, the end cap having latch grooves 645, 646 cooperating with the latches 565, 566. The movements of this insulator 640 are controlled by a pump connected to the trunk 563 through the ducts 564.

The drawings show the parts in position for connecting the upper busbar 562 to the fixed circuit-breaker contact, and the change-over to the lower busbar 572 can be effected on load by releasing the latch 566 and starting up the pump associated with the insulator 640 to drive oil from the upper part of the trunk 563 into the lower busbar chamber 570, thus raising the insulator 640 into its operative position wherein it is held by the latch 565, its contact 641 bridging the gap between the lower busbar contact 571 and the metal ring 613. Thus the two busbars are connected together and to the fixed circuit-breaker contact, and the change-over is completed by lowering the upper insulator 630 from its operative position. The change-over can alternatively be effected after first opening the circuit-breaker contacts by reversing the order of movement of the two insulators 630, 640 and afterwards reclosing the circuit-breaker. As in the arrangement of Figure 24 complete isolation of the circuit-breaker from the busbars can be effected by withdrawing the insulated conductor 590 to its lower isolating position, when the sluice valve

574 can be closed and the bellows 588 detached to allow removal of the circuit-breaker.

It will be appreciated that the arrangements above described have been given by way of example only and may be modified in various ways 5 within the scope of the invention.

What I claim as my invention and desire to secure by Letters Patent is:—

1. In metal-clad electric switchgear, the combination of a chamber containing insulating liquid 10 and having an orifice in its wall below the level of liquid in the chamber, a conducting member immersed in the insulating liquid in the chamber, a movable conductor which in its operative position projects through the orifice in the chamber 15 wall to make contact with the conducting member, means for withdrawing the movable conductor from the chamber, and a sealing device for sealing the orifice in a liquid-tight manner when the movable conductor has been withdrawn 20 from the chamber.

2. In metal-clad electric switchgear, the combination of two chambers each having an orifice in its wall, a conducting member immersed in insulating liquid in each chamber, a movable conductor which in its operative position projects through the orifices into both chambers to connect the two conducting members together, means for withdrawing the movable conductor from one of the chambers, and a sealing device for at least 30 one of the chambers so arranged as to seal the orifice therein in a liquid-tight manner when the movable conductor is in its withdrawn position.

3. In metal-clad electric switchgear, the combination of a tank containing insulating liquid, an electrical apparatus immersed in the liquid in the tank, a chamber containing insulating liquid and having an orifice in its wall below the level of liquid in the chamber, a contact immersed in the insulating liquid in such chamber, means for 40 connecting such contact to an external circuit, an insulated conductor mounted so that it can project into the tank and into the chamber to connect the contact in the chamber to a terminal of the apparatus in the tank but movable relatively to the tank and the chamber, means for withdrawing the insulated conductor from the chamber towards the apparatus tank, and means for sealing the orifice in the chamber wall in a liquid-tight manner when the insulated conductor 50 has been withdrawn therefrom.

4. In metal-clad electric switchgear, the combination of a tank containing insulating liquid, a circuit-breaker immersed in the liquid in the tank, two chambers each containing insulating liquid 55 and having an orifice in its wall below the level of liquid in the chamber, a contact immersed in the insulating liquid in each chamber, means for connecting the contacts in the chambers to external circuits, two movable insulated conductors which in their operative positions respectively pass through the orifices in the chamber walls and connect the two circuit-breaker contacts in the tank to the contacts in the two chambers, means for withdrawing each insulated conductor from the associated chamber towards the circuit-breaker tank, and means for sealing the orifice in each chamber wall when the associated insulated conductor has been withdrawn from the chamber.

5. In metal-clad electric switchgear, the combination of a fixed chamber containing insulating liquid and having an orifice in its wall below the level of liquid in the chamber, a contact immersed in the insulating liquid in the chamber and connected to an external circuit, a tank containing 75

- insulating liquid movably mounted with respect to the fixed chamber, an electrical apparatus immersed in the liquid in the tank, an insulated conductor carried by the tank and connected to the apparatus therein and so arranged that when the tank is in its operative position the conductor projects through the orifice in the chamber wall to connect the apparatus to the contact in the chamber, means for moving the tank relatively to the fixed chamber to withdraw the insulated conductor from the chamber, and means for sealing the orifice in the chamber wall in a liquid-tight manner when the tank has been moved to withdraw the insulated conductor from the chamber.
6. The combination with the features set forth in claim 5, of a detachable metal bellows which connects the tank and the fixed chamber around the insulated conductor and has such flexibility as to permit the tank to be moved from its operative position far enough to withdraw the insulated conductor from the fixed chamber without detaching the bellows.
7. In metal-clad electric switchgear, the combination of two chambers each having an orifice in its wall, a conducting member immersed in insulating liquid in each chamber, a metal trunk carried by the first chamber around the orifice therein, a flexible extension on the metal trunk, means for clamping the flexible extension to the second chamber in a liquid-tight manner around the orifice therein, a movable conductor which in its operative position passes through the metal trunk and connects together the conducting members in the two chambers, means for withdrawing the movable conductor from the second chamber, and a sealing device for sealing the orifice in the second chamber in a liquid-tight manner when the movable conductor has been withdrawn therefrom.
8. In metal-clad electric switchgear, the combination of a chamber containing insulating liquid and having an orifice in its wall below the level of liquid in the chamber, a conducting member immersed in the insulating liquid in the chamber, a movable conductor which in its operative position projects through the orifice in the chamber wall to make contact with the conducting member, means for withdrawing the movable conductor from the chamber, a valve movably mounted on the wall of the chamber, and means for moving the valve into position for sealing the orifice in a liquid-tight manner when the movable conductor has been withdrawn from the chamber.
9. In metal-clad electric switchgear, the combination of a tank containing insulating liquid, an electrical apparatus immersed in the liquid in the tank, a chamber having an orifice in its wall, a contact immersed in insulating liquid in such chamber, means for connecting such contact to an external circuit, an insulated conductor movably mounted so that it can project into the tank and into the chamber to connect the contact in the chamber to a terminal of the apparatus in the tank, means for withdrawing the insulated conductor from the chamber towards the apparatus tank, a metal trunk carried by the tank and surrounding the insulated conductor, a flexible extension on the metal trunk, means for clamping the flexible extension in a liquid-tight manner to a fitting on the chamber around the orifice therein, a valve movably mounted on the wall of the chamber, and means for moving the valve into position for sealing the orifice in the

chamber wall in a liquid-tight manner when the movable conductor has been withdrawn from the chamber.

10. In metal-clad electric switchgear, the combination of a chamber containing insulating liquid and having an orifice in its wall below the level of liquid in the chamber, a conducting member immersed in the insulating liquid in the chamber, a movable conductor which in its operative position projects through the orifice in the chamber wall to make contact with the conducting member, means for withdrawing the movable conductor from the chamber, a valve chest carried on the wall of the chamber adjacent to the orifice therein, a sliding sluice valve in the valve chest, and means for moving the sluice valve into a position in which it will seal the orifice in the chamber wall in a liquid-tight manner when the movable conductor has been withdrawn from the chamber.

11. In metal-clad electric switchgear, the combination of a tank containing insulating liquid, an electrical apparatus immersed in the liquid in the tank, a chamber containing insulating liquid and having an orifice in its wall below the level of liquid in the chamber, a contact immersed in the insulating liquid in such chamber, means for connecting such contact to an external circuit, an insulated conductor mounted so that it can project into the tank and into the chamber to connect the contact in the chamber to a terminal of the apparatus in the tank but movable relatively to the tank and the chamber, means for withdrawing the insulated conductor from the chamber towards the apparatus tank, a valve chest carried on the wall of the chamber adjacent to the orifice therein, a sliding sluice valve in the valve chest, and means for moving the sluice valve into a position in which it will seal the orifice in the chamber wall in a liquid-tight manner when the movable conductor has been withdrawn from the chamber.

12. In metal-clad electric switchgear, the combination of two fixed chambers each containing insulating liquid and having an orifice in its wall below the level of liquid in the chamber, a contact immersed in the insulating liquid in each chamber, a busbar connected to the contact in one chamber, means for connecting the contact in the other chamber to an external circuit, a tank containing insulating liquid movably mounted with respect to the fixed chambers, a circuit-breaker immersed in the liquid in the tank, two insulated conductors carried by the tank and respectively connected to the two contacts of the circuit-breaker therein the conductors being so arranged that when the tank is in its operative position they will connect the two circuit-breaker contacts respectively to the contacts in the two fixed chambers, means for moving the tank relatively to the fixed chambers to withdraw the insulated conductors therefrom, a valve chest carried on the wall of each fixed chamber adjacent to the orifice therein, a sliding sluice valve in each valve chest, and means for moving the sluice valves into position for sealing the orifices in a liquid-tight manner when the tank has been moved to withdraw the insulated conductors from the fixed chambers.

13. In metal-clad electric switchgear, the combination of a tank containing insulating liquid, a circuit-breaker immersed in the liquid in the tank, two chambers each having an orifice in its wall, a contact immersed in insulating liquid in each chamber, means for connecting the contacts

- in the chambers to external circuits, two movable insulated conductors which in their operative positions respectively connect the two circuit-breaker contacts in the tank to the contacts 5 in the two chambers, means for withdrawing each insulated conductor from the associated chamber towards the circuit-breaker tank, two metal trunks carried by the tank and respectively surrounding the two insulated conductors, a flexible extension on each metal trunk, a valve chest carried on the wall of each chamber adjacent to the orifice therein, means for clamping each flexible extension in a liquid-tight manner to the associated valve chest, a sliding sluice valve in 10 each valve chest, and means for moving each sluice valve into position for sealing the orifice in the chamber wall in a liquid-tight manner when the associated insulated conductor has been withdrawn from the chamber. 15
14. In metal-clad electric switchgear for a multi-phase circuit, the combination of a fixed chamber having an orifice for each phase in its wall, a contact in each phase immersed in insulating liquid in the chamber, a tank containing insulating liquid having an orifice for each phase in its wall, a multi-phase electrical apparatus immersed in the liquid in the tank, a terminal of the apparatus in each phase, a metal trunk connecting each orifice in the fixed chamber with 20 the corresponding orifice in the tank, a movable insulated conductor in each metal trunk acting when in its operative position to connect one of the contacts in the fixed chamber with the corresponding terminal of the apparatus in the tank, 25 means for withdrawing the insulated conductors from the fixed chamber, a valve chest on the wall of the fixed chamber adjacent to the orifices therein, a sliding sluice valve in the valve chest for each orifice, and a single device for operating 30 the sluice valves so that they can be moved into positions in which they seal the orifices in the fixed chamber wall in a liquid-tight manner when the insulated conductors have been withdrawn from the chamber. 35
15. In metal-clad electric switchgear, the combination of a tank, a power transformer immersed in insulating liquid in the tank, a second tank, a circuit-breaker immersed in insulating liquid in the second tank, a chamber having three orifices 40 in its wall, two contacts immersed in insulating liquid in the chamber, two movable conductors which in their operative positions respectively pass through two of the orifices in the chamber wall and connect the two circuit-breaker contacts to the two contacts in the chamber, a third movable conductor which in its operative position passes through an orifice in the chamber wall and connects the power transformer to one of the contacts in the chamber, means for connecting the other contact in the chamber to an external circuit, means whereby each movable conductor can be withdrawn from the chamber, and means for sealing each orifice in the chamber wall in a liquid-tight manner when the associated movable conductor has been withdrawn. 45
16. The combination with the features set forth in claim 15, of metal trunks carried by the tanks and respectively surrounding the movable conductors, a flexible extension on each metal trunk, and means for clamping each flexible extension to the wall of the chamber around the orifice therein, the arrangement being such that after the movable conductors have been withdrawn from the chamber and the orifices therein sealed the flexible extensions can be detached from the chamber to permit removal of the tanks together with the movable conductors from the switchgear. 50
17. In metal-clad electric switchgear, the combination of two chambers each having an orifice in its wall, a contact immersed in insulating liquid in each chamber, a movable conductor which in its operative position projects through the orifices into both chambers to connect the two contacts together, driving means for moving the conductor into its operative position or into an isolating position in which it lies wholly outside one of the chambers, a valve movably mounted on the wall of one of the chambers, means for moving the valve into position for sealing the orifice in the wall of such chamber in a liquid-tight manner 30 when the movable conductor is in its isolating position, and means for preventing operation of the driving means to move the conductor from its isolating position when the valve is closed. 35
18. The combination with the features set forth in claim 11, of interlocking devices for preventing closing of the sluice valve when the insulated conductor is in its operative position and for preventing movement of the conductor from its withdrawn position when the sluice valve is closed. 40

ARCHIBALD ALLAN.
